(57) **CLAIM**

The ornamental design for a control cabinet for robot, as shown and described.

DESCRIPTION

The file of this patent application contains at least one photograph executed in color. Copies of the patent application with color drawings will be provided by the Office upon request and payment of the necessary fee.

FIG. 1 is a front, left, and top perspective view of a first embodiment of a control cabinet for robot showing my new design;

FIG. 2 is a front, right, and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, left, and top perspective view of a second embodiment of a control cabinet for robot showing my new design;

FIG. 10 is a front, right, and top perspective view thereof;

FIG. 11 is a front elevational view thereof;

FIG. 12 is a left side elevational view thereof;

FIG. 13 is a right side elevational view thereof;

FIG. 14 is a top plan view thereof; and,

FIG. 15 is a bottom plan view thereof.

The broken lines in the figures are included for the purpose of illustrating portions of the article which form no part of the claimed design.
